UNITED STATES PATENT OFFICE.

ERNEST C. PAGEL AND SIDNEY W. TREAT, OF CHICAGO, ILLINOIS, ASSIGNORS TO CONSOLIDATED STEEL STRAPPING COMPANY, OF CHICAGO, ILLINOIS, A CORPORATION OF DELAWARE.

PACKAGE.

Application filed June 19, 1925. Serial No. 38,164.

Our invention relates to a package, and more particularly to a package which will protect a stack of metal plates or other flat articles, and which will facilitate the shipment and handling thereof.

Steel and other metal plates, both plain and lithographed, are used for a great variety of industrial purposes. To be economically handled and shipped, they must be packaged or crated in units each consisting of a plurality of superposed plates.

Heretofore it has been difficult, on account of the excessive weight of the plates when assembled, securely to package and handle the same. Crates which are nailed together or screwed together for the carrying of such plates are invariably of excessive bulk and are subject to the very serious objection that the nails or screws of the crate often start out in handling and cause serious wounds. Moreover, such crates are usually so much damaged in shipment that it is not feasible to use them a second time. Furthermore, it is impracticable to reship the crates ordinarily employed on account of their bulk and the labor involved in knocking them down and reconstructing them.

With these considerations in view, our invention contemplates the provision of:

(a) A package of stacked plates which, while very rugged and secure, is only slightly larger than the stack of plates which it contains.

(b) A package of stacked plates which need be only slightly heavier than the unpacked plates.

(c) A package of stacked plates which is or may be formed entirely of metal.

(d) A package of stacked plates which may be held together by metallic strapping.

(e) A package of stacked plates which readily may be moved edgewise over a floor or other surface.

(f) A package of stacked plates which may be moved edgewise over a floor or other surface without dislocating the metallic strapping by which the package is held together.

(g) A package formed by devices which, with the exception of the box strapping, may be used repeatedly, and which when not in use occupy very little space.

(h) A package so constructed as to afford the stack of metal plates or the like maxi-

mum protection at the points where they require protection most—that is, at the edges of the plates.

(i) A package comprising plate engaging elements which, unlike the usual wooden crate, are adapted firmly to hold the plates against play within the package.

(j) A package of metal plates or the like which presents surfaces of substantial area adapted to bear advertising matter and the like.

Other features, objects and advantages of our invention will appear from the following detailed description, wherein reference is made to the accompanying drawing, in which

Figure 1 is a side elevational view of a completed package employing the devices of our invention;

Figure 2 is a side elevational view on a larger scale, of one of the channel members;

Figure 3 is a fragmentary sectional view through one edge of the completed package, showing the engagement of the plates in the channel members;

Figure 4 is a transverse sectional view through one of the channel members; and

Figure 5 is a similar view showing how these channel members nest together for shipment or storage.

The lithographed plates, sheets, or other articles which are to be packaged are indicated at 8 (Fig. 2), it being understood that these sheets or plates 8 are representative of any flat article or articles which it is desired to bind together in package form. Where such sheets or plates have surfaces which it is desired to protect, intervening sheets 9 of fibre, pasteboard, or any other suitable material may be placed between the plates or articles as further shown in Fig. 3. Such protecting sheets 9 may also be placed over the outer sides of the outermost plates 8 for protecting the outer surfaces thereof.

After the plates, and whatever protecting sheets may be employed, have been stacked or brought together as shown in Fig. 3, the edges of the stack or group of plates are enclosed in metallic border members 11 of channel shaped section. These border members consist of sections of channel stock cut to lengths appropriate for the desired package and formed in the manner which we shall now describe. Each of these channel sec-

tions comprises a web portion 11^a and side flanges 11^b of sufficient depth securely to overlap and embrace the edges of the plates or other articles. These side flanges 11^b 5 may extend in parallel relation, but for facility in nesting and for other reasons which will hereinafter be apparent, we prefer to flare these side flanges outwardly at a slight angle, substantially as shown in 10 Figs. 4 and 5. Punched outwardly in the web portion 11^a of these channel sections are spaced protuberances 11^c which form projecting nipples or bosses of spherical form. These nipples or bosses provide 15 smooth sliding surfaces for the package and also act as anchoring means for the strapping, which we shall presently describe.

In fitting the border channels 11 over the group of plates 8 and sheets 9, the ends of 20 the channels may be nested one within the other at the corners of the package in any preferred manner; to-wit, the end channels may be slipped over the ends of the top and bottom channels or vice versa, or the 25 nesting of one channel within the end of the other may be alternated at the corners. The flanges are sufficiently ductile so that this can be performed without any difficulty, and this nesting at the corners is facilitated 30 by the flare of the lateral flanges 11^b, which enables the flared edges of the outer channel to be started over the narrow part of the inner channel and then swung into position against the edge of the package. The 35 outward flare of the two side flanges 11^b also facilitates the placing of the channels over the edges of the plates, these side flanges affording wedging surfaces which snugly bind the plates together.

40 The strapping preferably comprises two or more metal straps 12 passed around the package in each dimension, these straps being preferably located near the corners of the package. The straps are drawn taut 45 by the use of a suitable tensioning tool, and the ends of the straps are then joined together by suitable seals 13. The stretching of the straps may be performed by a stretching tool such as that disclosed in Patent No. 50 1,453,564 issued to Arthur G. G. Guenther, and the ends of the straps may be joined together by Signode seals such as those described in Patent No. 1,252,680 issued to E. E. Flora. In placing the straps around 55 the package, care is taken so that each of the straps will pass over the border channels 11 at points between the protuberances 11^c.

60 When completely assembled, the package forms a substantially rigid shipping unit affording a maximum degree of protection to the plates. The metallic border members give complete protection to the edges of the plates, which generally are the most vulnerable points of such a package. In addition,

a package of this type avoids all play or end motion of the plates within the confines of the package. This will be obvious from the fact that the tension of the strapping holds the border channels in firm engagement with the edges of the plates. With the channel members arranged as shown in Fig. 1, the tension of the vertical straps tends to draw the upper and lower channels into binding engagement with the upper and lower edges 70 of the plates, and the tension of the horizontal straps tends to draw the end channels into locking engagement with the upper and lower channels. If the upper and lower channels extend slightly beyond the ends of the plates, the horizontal straps may be drawn sufficiently tight to flex or bow the intermediate portions of the end channels into firm engagement with the end edges of the plates. The outwardly flaring side flanges 75 11^b are stressed inwardly by the tension of the straps, and the outward pressure of these side flanges tends to maintain the straps under continuous tension. By the use of these metallic border channels, the straps can be drawn up under a very heavy tension 80 without any danger of the straps biting into the edges of the plates or other articles.

The presence of the nipples or bosses 11^c on the channels prevents any of the straps slipping sufficiently far along the channels to become disengaged therefrom. These nipples or bosses provide smooth, rounded sliding surfaces which enable the package to be slid very readily over a floor or other surface without cutting or marring the same. It will also be noted that there is an entire absence of nails, screws or any other sharp or pointed surfaces which might inflict 90 wounds in handling.

The name and address of the consignee, and any desired advertising matter may be printed on the side of the package (Fig. 1) on the outer fibre protecting sheet 9, or directly on the outermost plate or like article 100 where no outer protecting sheet is employed.

An advantage of great importance inherent in the present package over a wooden box or similar container, is that the channel sections are re-usable. This is made of 115 greater value by being able to nest the several sections together in a comparatively small bundle, as shown in Fig. 5; although where channels having parallel side flanges are employed, it will be evident that these 120 sections can also be bound together in a small bundle by placing the flange of one channel between the flanges of another channel, etc. When the channels are thus bound together in a small bundle, they can 125 be returned to the shipper with much greater convenience and a considerable saving in freight charges. When the channel sections are thus reused, the only material of the package which is lost is the strapping. The 130

ability to nest the sections together also enables the packaging materials for a large number of packages to be stored in a comparatively small space. The present package weighs much less than an average wooden box; as illustrative of this, the package in one particular size, aside from the weight of the contents, weighs $7\frac{1}{4}$ pounds, as against $11\frac{3}{4}$ pounds for an average box of 10 corresponding size.

Although in the drawing and in the above description, we have confined ourselves to what we consider the preferred embodiment of this invention, it is to be understood that 15 various modifications are contemplated, and the invention should, therefore, be limited merely by the scope of the appended claims.

Having now described our invention, what we consider as new and desire to secure by 20 Letters Patent is:

1. The combination with a relatively flat article, of a plurality of channels embracing the edges of said article and a strapping passed over said channels to retain them in 25 engagement with the flat article, each of the channels being provided with a plurality of

longitudinally spaced protuberances in their web portions only, extending throughout the length thereof, for holding the strapping in place, said protuberances being spaced apart 30 a distance slightly greater than the width of said strapping.

2. In a shipping package for metal sheets, the combination of a stack of metal sheets with a pair of frame members comprising 35 channeled members having diverging flanges in wedging engagement with the opposite sides of said stack of sheets at the edges thereof, a pair of similar frame members having diverging flanges in wedging engagement with the opposite sides of said stack at the ends of said first mentioned frame members and binder members arranged transversely about said stack and frame members to draw said frame members 40 into wedging engagement with the edges of said sheets and maintain said sheets in a compact stack.

In witness whereof, we hereunto subscribe our names this 13th day of June, 1925.

ERNEST C. PAGEL.
SIDNEY W. TREAT.
